(57) **CLAIM**

The ornamental design for a chair, as shown and described.

DESCRIPTION

FIG. 1 is a left front overhead perspective view of a chair showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front left underside perspective view thereof;

FIG. 9 is a rear left underside perspective view thereof;

FIG. 10 is a left front overhead perspective view of a second embodiment of the chair;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a front left underside perspective view thereof;

FIG. 18 is a rear left underside perspective thereof;

FIG. 19 is a left front overhead perspective view of a third embodiment of the chair;

FIG. 20 is a front elevational view thereof;

FIG. 21 is a rear elevational view thereof;

FIG. 22 is a left side elevational view thereof;

FIG. 23 is a right side elevational view thereof;

FIG. 24 is a top plan view thereof;

FIG. 25 is a bottom plan view thereof;

FIG. 26 is a front left underside perspective view thereof; and,

FIG. 27 is a rear left underside perspective view thereof.

The broken lines showing features of the design are for the purpose of illustration only and form no part of the claimed design.

1 Claim, 27 Drawing Sheets
